UNITED STATES PATENT OFFICE.

JOSEPH KARL, OF WEST PULLMAN, ILLINOIS.

ACETYLENE-GAS GENERATOR.

1,155,422.

Specification of Letters Patent.

Patented Oct. 5, 1915.

Application filed November 20, 1914. Serial No. 873,136.

To all whom it may concern:

Be it known that I, JOSEPH KARL, a citizen of the United States, residing at West Pullman, county of Cook, State of Illinois, have invented a certain new and useful Improvement in Acetylene-Gas Generators, and declare the following to be a full, clear, and exact description of the same, such as will enable others skilled in the art to which it pertains to make and use the same, reference being had to the accompanying drawings, which form a part of this specification.

My invention has for its object to produce a simple and novel construction in which the containing and feeding devices of a generating plant will be so constructed that there will remain in the feeding devices sufficient calcium carbide to permit the plant to operate in an ordinary way for a considerable period after the main tank or hopper has become empty.

A further object of my invention may be said to be to produce a simple and novel feeding device for acetylene gas generators.

The various features of novelty whereby my invention is characterized will herein-after be pointed out with particularity in the claims; but, for a full understanding of my invention and of its objects and advantages, reference may be had to the following detailed description taken in connection with the accompanying drawing, wherein:

Figure 1 is a central vertical section taken through a plant arranged in accordance with a preferred form of my invention; Fig. 2 is a section on line 2—2 of Fig. 1; Fig. 3 is a section on an enlarged scale in the same plane as Fig. 1, showing the construction of the feeding devices; Fig. 4 is a section taken approximately on line 4—4 of Fig. 3; and Fig. 5 is a top plan view of the parts shown in Fig. 3, with the hopper removed.

Referring to the drawing, 1 represents a generating reservoir adapted to contain water to the level of the dotted line 2; 3 is the gas-receiving tank or reservoir adapted to contain water to the level of the dotted line, 4; and 5 is a gas bell; all of these parts being of any usual or preferred forms or types.

The upper portion of the main reservoir, above the water level, is divided into two parts, 6 and 7, having flanges, 8, at their

meeting edges by means of which they may be fastened together. The hopper, 9, and the feeding devices are detachably arranged within the upper portions of the main reservoir, there being in the arrangement illustrated an open-ended shell or casing, 10, provided at its upper edge with laterally projecting flanges, 11, adapted to rest between the flanges 8 of the members 6 and 7. Lying in the upper end of the shell 10 are two connected plates, 12, having at the upper edges flanges, 13, resting on the flanges 11 at the long sides of the casing and approaching each other at their lower ends, the plates being connected by two cross plates, 14 and 15, spaced apart farther at their upper ends than at their lower ends, thus forming with the plates 12 a small hopper open at the top and at the bottom. The main hopper, 9, rests upon or forms part of this small hopper, so that the small hopper is simply the outlet end of a main calcium carbide reservoir.

Just below the plates 12 are ledges, 16, extending inwardly from the four corners of the casing 10, and on these ledges is arranged a trough-like member or container of the feeding devices; this member or container consisting simply of a flat plate, 17, of considerable length, lying below the mouth of the hopper and provided at the side edges with upstanding vertical side pieces, 18, substantially the same length as the width of the casing, the side pieces 18 being provided with flanges, 19, adapted to rest on the ledges 16. The plate, 17, is shorter than the width of the casing 10 and is so positioned that there is a space between each of its ends and the corresponding sides of the casing.

Lying on top of the side pieces 18 is a feeding plate or valve, 20, whose side edges are bent over as indicated at 21 to embrace the edges of the flanges, 19, on the side pieces, 18. At one end, which may be termed the front end, the plate 20 is bent downwardly as indicated at 22, between the two side pieces 18 into proximity with the top of the plate 17.

The parts are so proportioned that the plate 20 may be moved laterally along the stationary member of the feeding device, carrying the pusher end, 22, across the plate 17 from one end of the latter to the other;

carbid flowing down from the hopper upon the plate 17 when the member 20 is retracted, and the mouth of the hopper being closed by the member 20 when the latter is moved toward the right a predetermined distance.

It will thus be seen that the hopper and the feeding devices are all readily detachable and are of such a nature that they may conveniently be fitted into existing tanks or reservoirs. Thus, by taking off the upper member 7 of the main reservoir, the plates 12 and the parts connected therewith may be lifted out, thus leaving a clear space above the feeding devices and permitting these to be lifted out; or, the auxiliary casing, 10, may be lifted out as a single unit, leaving the lower end of the hopper, and the feeding devices undisturbed in their relation to each other and to the casing 10.

The slide 20 is actuated by the falling movements of the gas bell, through suitable lever mechanism and connections which will normally hold the slide retracted, that is adjacent the right hand end of the plate 17 as viewed in Figs. 1 and 3. In the arrangement shown, there is a bell crank lever, 25, mounted between ears, 26, which project downwardly from the members 18 of the stationary part of the feed mechanism. One arm of the bell crank lever is connected to the slide, 20, by means of a link, 27. To the other arm of the lever is secured a depending rod, 24, which is connected at its lower end, at a point below the water level in the main reservoir, to a horizontally projecting arm, 28, on the lower end of a rod, 29, which projects upwardly out of the top of the enlarged lower portion of the main reservoir; the rod, 29, passing through a tube, 29^a, so arranged as to form a water seal. The upper end of the rod 29 is secured to one end of a pivotal lever, 30, the other end of which lies in the path of movement of a finger, 31, carried by the gas bell 5 in the gas holder.

The parts are so proportioned that normally the weight of the links and levers causes the slide 20 to be retracted until arrested by some suitable stop as, for example, a pin or pins, 32, in position to engage with the rear end of the slide and holding the slide with its depending pusher plate 22 just at the left of the mouth of the hopper.

Assuming the plant to be in operation with the hopper 9 containing a supply of carbide which flows out upon and to the right hand edge of the plate 17, and that the gas is being withdrawn from the bell faster than it is being generated: The bell will gradually sink until the finger, 31, engages with the lever, 30, as indicated in Fig. 1 of the drawing, at which time the bottom of the bell is at a considerable distance above the bottom of the reservoir, 3, and a continued

downward movement of the bell will result in a movement of the slide 20 toward the right, causing some of the carbide to drop over the edge of the plate 17 and into the water below. This results in a rapid generation of gas, so that before the bell has fallen more than half an inch or so, the gas will be supplied to it in sufficient quantities to cause it to rise in the usual way. As soon as the bell rises, the slide and its operating mechanism resume their normal positions and a sufficient quantity of carbide flows from the hopper down upon the plate 17 to compensate for that which was dropped down into the water on the preceding feeding movement. As the gas generated from the charge just fed into the water is consumed, the bell again begins to settle until it causes a new charge to be fed in the manner heretofore described. When the hopper is empty there is still a considerable amount of carbide on the plate 17 so that thereafter the bell must settle a little lower each time in order to deliver a charge of carbide, the stroke of the slide gradually increasing until finally the bell settles on the bottom of the reservoir 3 and either the accompanying movement of the slide is insufficient to push any more carbide from the platform or plate 17 or, depending upon the proportion of the parts, the supply of carbide is entirely exhausted.

The value of maintaining what may be termed a reserve supply of carbide in the feeding devices is that the user will always know, as long as there is any carbide in the hopper, that the plant will be operative for at least a predetermined length of time. In other words, he will know that if there is any carbide in the hopper in the evening the plant will be operative, for example, until the next morning so that there will be no danger of the lights going out during the night.

If desired, a suitable alarm or signaling device of any kind may be associated with the apparatus so that whenever the hopper becomes empty and the bell sinks below the predetermined point at which a normal charge is ordinarily fed, an alarm is sounded or a signal given to apprise the user of the fact that the hopper is empty. In the arrangement shown, there is a small electrically operated bell, 40, in the circuit of which is a small controlling switch, 41, in the path of movement of a finger, 42, on the bell. The finger does not close a circuit through the alarm bell unless the gas bell settles below the point necessary for a normal feeding movement of the slide 20.

While I have illustrated and described with particularity only a single preferred form of my invention, I do not desire to be limited to the exact structural details thus illustrated and described; but intend to cover all forms and arrangements which

come within the terms employed in the definitions of my invention constituting the appended claims.

I claim:

5. 1. In an apparatus of the character described, a generating reservoir, a gas receiving bell, a hopper for containing calcium carbide, an elongated trough lying beneath the hopper and adapted to receive carbide 40 therefrom, a slide movable lengthwise in said trough to discharge carbide therefrom and having a part serving as a valve to close the outlet end of the hopper, said trough being of sufficient length to hold a considerable 45 number of individual charges of carbide, and operating connections for said slide including a device in the path of movement of a part on the bell, said operating connections having no positive connection with the bell 50 and tending constantly to hold said slide in one end of the trough, the parts being so constructed and arranged that upon each descent of the bell to a predetermined point it causes said slide to move from the normal 55 starting point a distance sufficient to feed a single charge into the reservoir until the hopper is empty, while, after the hopper becomes empty successive descents of the bell to points below said predetermined 60 point cause the slide to move from said normal starting point in constantly increasing strokes until the trough is empty.
25. 2. In an apparatus of the character described, a casing open at the top, inwardly projecting shoulders on the casing in a plane below the top, a flanged trough extending across said casing and having its flanges 30 resting on said shoulders, the member forming the bottom of the trough being cut away at each end, a hopper supported in the casing above said trough, a combined pusher and valve for the hopper arranged within 35 said trough.
3. In an apparatus of the character described, a generating reservoir, a gas receiving bell, a hopper for containing calcium carbide, an elongated trough lying beneath the hopper and adapted to receive carbide 40 therefrom, a slide movable lengthwise in said trough to discharge carbide therefrom and having a part serving as a valve to close the outlet end of the hopper, said trough being of sufficient length to hold a considerable 45 number of individual charges of carbide, and operating connections for said slide including a device in the path of movement of a part on the bell, said operating connections having no positive connection with the bell 50 and tending constantly to hold said slide in one end of the trough, the parts being so constructed and arranged that upon each descent of the bell to a predetermined point it causes said slide to move from the normal 55 starting point a distance sufficient to feed a single charge into the reservoir until the hopper is empty, while, after the hopper becomes empty successive descents of the bell to points below said predetermined 60 point cause the slide to move from said normal starting point in constantly increasing strokes until the trough is empty.

In testimony whereof, I sign this specification in the presence of two witnesses.

JOSEPH KARL.
